UNITED STATES PATENT OFFICE.

HENRY CREAMER, OF NEW YORK, N. Y.

STEAM-TRAP AND FEEDER.

SPECIFICATION forming part of Letters Patent No. 394,463, dated December 11, 1888.

Application filed June 27, 1888. Serial No. 278,331. (No model.)

To all whom it may concern:

Be it known that I, HENRY CREAMER, of the city of New York, county of New York, State of New York, have invented certain new and useful Improvements in Steam-Traps and Feeders, of which the following is a specification.

This invention relates to certain new and useful improvements in that class of machines known as "steam-traps and feeders," and which serve for the purpose of conducting water of condensation from steam pipes, radiators, engines, &c., back into the boiler.

The object of my invention is to provide a new and improved steam-trap, which is simple in construction, effective in use, and not liable to get out of order.

The invention consists in the combination, with a steam-cylinder, of a water-cylinder in the same, closed at its lower end and open at its upper end, a piston formed on each end of the water-cylinder, a neck fitting closely in said inner or water cylinder, and suitable valves and mechanism for operating the same.

The invention also consists in the construction and combination of parts and details, as will be fully described and set forth herein-after, and pointed out in the claims.

In the accompanying drawings, Figure 1 is a vertical transverse sectional view of my improved steam-trap, showing the piston lowered. Fig. 2 is a similar view showing the piston partially raised. Fig. 3 is a diagrammatic view showing the connections between the boiler and the steam-trap.

Similar letters of reference indicate corresponding parts.

The cylinder A, which is turned off smooth on its inside, is provided with a bottom head, A', and a top head, A², secured on the ends of the cylinder in the usual well-known manner. The water-cylinder C, having less diameter than the steam-cylinder A, is closed at its bottom and provided at its top and bottom with exterior annular pistons, C' and C², respectively, said pistons fitting closely within the steam-cylinder and being provided with grooves for receiving suitable packing. The top head, A', of the steam-cylinder is provided on its under side with a downwardly-projecting neck, D, the lower end of which fits closely within the water-cylinder C, said

neck being provided at its lower end with exterior annular grooves for receiving packing.

The neck D may be contracted for a part 55 of its length between its upper and lower ends for the purpose of increasing the space between the inner surface of the upper part of the steam-cylinder A and the outer side of said neck. The top head, A', of the steam-cylinder A is provided with an opening, B, of the same diameter as the top part of the neck D, and above said opening the bonnet E is held by suitable bolts on the upper surface of said top head. A shaft, F, journaled 60 transversely in one part of the bonnet, has one end projecting beyond the bonnet, which end is provided with an arm, F', to which one end of the check-rod G is pivoted. Within the bonnet an arm, H, projects from the shaft 65 F, and from the swinging end of said arm the float J is suspended within the enlarged upper end of the neck D.

On the upper surface of the top head, A', the valve-casing K is secured, in which the 75 rocking valve L is mounted to turn, said valve being rigidly mounted on the transverse shaft M, provided at one end with the arm M' carrying the weight M². Adjacent to said arm M', or, if desired, on the opposite end of the 80 shaft M and outside of the valve-casing, the sleeve N is loosely mounted on the shaft M, and is provided with a notch, N', the ends of which can engage a pin or stud, N², projecting from the shaft M. Said sleeve N is provided with an arm, O, connected by a rod, O', with the outer end of an arm, P', on a transverse shaft, P, journaled in a projection, Q, of the steam-cylinder. Within said projection an arm, R, projects from the shaft P into the 90 interior of the steam-cylinder and into the space between the top and bottom pistons, C' and C², of the water-cylinder C.

The channel S, for the exhaust-steam, leads from the valve-casing K to the top of the 95 steam-cylinder, and another channel, T, leads from the valve-casing K through a suitable projection on the outside of the steam-cylinder to the bottom of said steam-cylinder. As shown in the drawings, it would seem that 100 said channel T was closed by the projection Q; but said channel is curved around said projection, or the channel is arranged at one side of the same. The rocking valve L is

provided in its rim with a recess, V, and the casing K is provided on its inside with a recess, I.

That end of the rod G opposite the one connected with the arm F' is guided by a suitable lug, G³, on the valve-casing K. The channel a leads, within the top head A', from the channel S to the opening B in said top head, and the end of the channel a is closed by a screw-plug, b, which can also be screwed into the lower end of the channel S. The projection Q on the side of the steam-cylinder is provided with an opening with which a pipe, d, is connected, which pipe is also connected with the pipe r or m. The valve-casing K has a neck, g, for receiving the pipe h, that conveys live steam to the valve. The pipe o serves to conduct the water of condensation into and out of the trap, and is connected with a pipe, m, that conveys the water from the return-pipe and with a pipe, r, leading to the boiler. The pipe m is provided with a check-valve, m', and pipe r with a check-valve, r', both opening in the same direction.

25 The operation is as follows: As shown in Fig. 1, the trap is empty and the water-cylinder and its pistons are lowered. The live steam is shut off and the water from the returns passes through the pipes m and o into the bonnet E, flows over the float J, through the neck D into the water-cylinder C, in which it accumulates and rises. When said water-cylinder is filled, the water rises in the neck D and finally raises the float J, whereby the arm H is swung upward. Thereby the arm F', which is on the same shaft F with the arm H, is moved in the direction of the arrow x', and the rod G is moved in the direction of the arrow x² and from the arm M', which it has supported, thus permitting the said arm to swing under the action of its weight M² in the direction of the arrow x³. Thereby the valve L is turned in the direction of the arrow x³ and brought into position. (Shown in Fig. 2.)

45 The upper end in the channel S is now closed, and the recess V establishes communication between the recess I and the upper end of the channel T, permitting the live steam to pass through the channel T to the bottom of the steam-cylinder and below the piston C² of the water-cylinder C.

I will here state that the swinging of the arm M' in the direction of the arrow x³ does not move the arm O, and only brings the pin 55 N² against the right-hand end of the notch or slot N' in the sleeve N, from which the arm O projects, the arms R and P' remaining in the position shown in Fig. 1. The live steam, passing into the bottom of the steam-cylinder, 60 forces the piston C² and the water-cylinder on the same upward, whereby the water in the neck D is forced out through the pipe o and into the boiler through the pipe r, the float J being kept in the raised position. At the 65 same time the pistons C' C² on the water-cylinder force the exhaust-steam of the previous stroke, and which is now in that space of the

steam-cylinder bounded by the upper part of said steam-cylinder and the neck D, out through the pipe d and into the pipe r or m. 70

The piston C' has a series of apertures, n', through which the exhaust-steam can pass as said piston rises, that part of the steam that passes through said apertures being forced out of the steam-cylinder into the pipe d by the 75 top of the bottom piston, C². The water-cylinder C continues its upward movement until the top of the bottom piston, C², strikes the end of the arm R, and, swinging the same into the position shown in Fig. 2 in 80 dotted lines, whereby the arm P' is moved downward, the rod O' is pulled downward and the arm O swung in the direction of the arrow x⁴. The end of the notch or slot N', acting on the pin N², turns the shaft M in the 85 inverse direction of the arrow x³, whereby the arm M' and its weight M² are raised—that is, swung in the inverse direction of the arrow x³. The valve L is thus brought into the position shown in Fig. 1. The communication 90 between the pipe h and steam-channel T is interrupted, and the channel S is connected with the channel T. The cylinder C now begins to descend, under the action of its own weight, and the water still contained therein, 95 thus permitting the float J to descend, whereby the arm F' is moved in the inverse direction of the arrow x⁴, and the rod G is moved in the inverse direction of the arrow x³. The end of the rod F' is brought against the raised 100 arm M', forming a stop of the same and preventing it from swinging in the direction of the arrow x³. As the water-cylinder and its pistons descend, the exhaust-steam—that is, the steam in the lower part of the steam-cylinder and below the piston C'—is forced up 105 through the channel T, through the recess V of the valve L, and through the channel S in the top part of the steam-cylinder. Just before the water-cylinder completes its down-stroke the under side of the upper piston, C', strikes the end of the arm R' swinging the same downward, whereby the arm P' and the rod O' are raised, and the arm O' is brought into the position shown in Fig. 1 without in 110 any way affecting the arm M'. The water now again accumulates in the water-cylinder. After a time the float is raised, the arm M' is released, the valve L is turned, and the above-described operation repeated. 115

To adjust the trap for pumping cold water at the same time that it forces the returns into the boiler, the bonnet E is removed, the plug b is removed from the end of the channel a, the top head, A', of the cylinder A is removed, and said plug b is screwed into the lower end of the channel S to close the same, and then the head A' and bonnet E are replaced. The pipe d is now connected with a pipe having opposite check-valves, as shown 125 in dotted lines in Fig. 2, and connected with the tank or pipe from which the water is to be pumped and the tank or receptacle into which the water is to be pumped. When the 130

pistons C' and C² descend, they create a vacuum between the inner surface of the cylinder A and the outer surface of the water-cylinder C and the neck D, whereby water is drawn from the tank into said space. At the same time the exhaust-steam below the piston C² is forced through the channel T, the valve L, the channel S, and the channel a into the bonnet, where it is condensed and mixed with the water flowing into and through the neck D.

When the steam forces the pistons C' and C² and the cylinder C upward, the cold water that has been drawn into the space between the inner surface of the cylinder A and the exterior surface of the cylinder C and neck D is forced out through the pipe d into the receptacle provided for this purpose and can be raised to the desired elevation at the same time the warm water in the water-cylinder C and neck D is forced out in the manner previously described. The pump thus serves at the same time for conveying the water of condensation or returns into the boiler and at the same time pumping and elevating cold water.

Having thus described my invention, I claim as new and desire to secure by Letters Patent—

1. In a steam-trap, the combination, with a cylinder, of a piston in the same, an interior cylinder formed upon said piston, and a neck fitting closely on said interior cylinder, substantially as herein shown and described.

2. In a steam-trap, the combination, with a cylinder, of a piston in the same, an interior cylinder formed upon said piston and provided at its upper end with an exterior flange fitting against the inner surface of the exterior cylinder, and a neck projecting from the upper head of said exterior cylinder into the open end of the interior cylinder, substantially as herein shown and described.

3. In a steam-trap, the combination, with an exterior cylinder, of a piston in the same, an interior cylinder on said piston, a neck projecting from the top head of the exterior cylinder into the upper open end of said interior cylinder, a float within said neck, and a valve controlled by said float, substantially as herein shown and described.

4. In a steam-trap, the combination, with an exterior cylinder, of a piston in the same, an interior cylinder formed upon said piston, a neck projecting from the top head of said exterior cylinder into the upper open end of said interior cylinder, a float within said neck, and a valve controlled by said float, the exterior cylinder and its head being provided with channels connecting the valve with the top and bottom of said exterior cylinder, substantially as herein shown and described.

5. In a steam-trap, the combination, with an exterior cylinder, of a piston in the same, an interior cylinder formed upon said piston, a neck projecting from the top head of said ex-

terior cylinder into the upper open end of the interior cylinder, and a pipe communicating with the space between the inner sides of the exterior cylinder and outer sides of the interior cylinder and neck, substantially as herein shown and described.

6. In a steam-trap, the combination, with an exterior cylinder, of a piston in the same, an interior cylinder formed on said piston, a neck projecting from the top head of said exterior cylinder into the upper open end of the interior cylinder, a float in the upper end of said neck, a bonnet on the top head of the exterior cylinder, and a valve controlled by said float, substantially as herein shown and described.

7. In a steam-trap, the combination, with an exterior cylinder, of a piston in the same, an interior cylinder formed on said piston, a neck projecting from the top head of the exterior cylinder into the upper open end of the interior cylinder, a float in the said neck, a rocking shaft having an arm from which the float is suspended, an additional arm on said rocking shaft, a check-rod connected with said additional arm, a rock-valve and a weighted arm for operating said valve, which arm can swing against the above-mentioned check-rod, an arm for operating the valve, a rock-shaft in the side of the exterior cylinder, an exterior arm of said rock-shaft connected with the arm for operating the valve, and an interior arm on said rock-shaft projecting into the exterior cylinder, substantially as herein shown and described.

8. In a steam-trap, the combination, with an exterior cylinder, of a piston in the same, an interior cylinder formed on said piston, a neck on the top head of the exterior cylinder, a float in said neck, a valve controlled by said float, a rock-shaft on the side of the exterior cylinder, an arm projecting from said shaft into the cylinder, and a rod connecting said rock-shaft with the above-mentioned valve, substantially as herein shown and described.

9. In a steam-trap, the combination, with a steam-cylinder, A, and its head A', said cylinder-head and easing having steam-channels S, T, and a, of the valve-easing K, the plug b, the valve L in the casing K, the piston C² and cylinder C, the neck D, and the float J, substantially as herein shown and described.

10. The combination, with a cylinder, of a piston in the same, a float in the cylinder, a valve acted upon by said float, and a lever in the path of the piston and connected with said valve, substantially as herein shown and described.

In testimony that I claim the foregoing as my invention I have signed my name in presence of two subscribing witnesses.

HENRY CREAMER.
